[57] CLAIM

The ornamental design for height adjustment handle for
suspending a grid on a barbecue grill, as shown and
described.

DESCRIPTION

FIG. 1 is a height adjustment handle for suspending a
grid on a barbecue grill showing my new design, the
grid is shown in broken lines for illustrative purposes
only and forms no part of the claimed design;
FIG. 2 is a left side elevational view thereof;
FIG. 3 is a front elevational view thereof;
FIG. 4 is a right side elevational view thereof;
FIG. 5 is a rear elevational view thereof;
FIG. 6 is a top plan view thereof; and
FIG. 7 is a bottom plan view thereof.
